WRITING MACHINE

John Q. Sherman and Albert W. Metzner, Dayton,
Ohio; said Metzner assignor to said Sherman

Application October 10, 1934, Serial No. 747,725

24 Claims. (Cl. 197—133)

This invention relates to writing machines of the flat bed type wherein an imprinting apparatus travels to and fro over a stationary platen upon which record material may be disposed in writing position, and more particularly to means for automatically ejecting an inscribed portion of record material and presenting a succeeding portion thereof in writing position.

To facilitate operation at increased speed, it is quite desirable that at the completion of the writing operation the inscribed form shall be removed and a succeeding form positioned in writing position with minimum effort and by rapid operation.

To this end the present invention pertains to an attachment readily applicable to existing writing machines of the type mentioned embodying motorized feeding means for intermittently advancing succeeding portions of continuous strips of record material predetermined distances past writing position, and control means for synchronizing the operation thereof with that of the writing machine, whereby the normal and customary manipulations of the writing machine will effect automatic advancement of the writing material.

The object of the invention is to improve the mechanism as well as the means and mode of operation of flat bed traveling typewriters and analogous writing mechanisms whereby they may not only be economically manufactured, but will be more efficient in use, automatic in action, uniform in operation, easily controlled, convenient, and unlikely to get out of repair.

A further object of the invention is to provide automatic material feeding mechanism for ejecting a portion of record material of predetermined length from the machine and advancing a succeeding like length of material into writing position in response to certain predetermined manipulations of the writing machine by the operator.

A further object of the invention is to provide efficient safety means by which unintentional ejection of record material will be obviated.

A further object of the invention is to provide motorized material feeding mechanism for intermittently advancing record material from a source of supply to writing position and simultaneously ejecting inscribed portions thereof.

A further object of the invention is to provide electrically controlled means for progressively advancing successive portions of record material into and out of writing position and to

provide safety means for preventing inadvertent operation thereof.

A further object of the invention is to provide multiple control devices for the record material feeding mechanism, a plurality of which must be operated by different agencies to enable the operation of the feeding mechanism.

A further object of the invention is to provide electrical control circuit for the record material feeding mechanism having therein multiple circuit breakers, one of which is closed by movement of the imprinting mechanism to predetermined position and the other of which is closed in response to manual operation by the operator.

A further object of the invention is to prevent operation of the feeding means for the advancement of the record material until the portion of material clamped in writing position has been released.

A further object of the invention is to prevent operation of the material feeding means until the imprinting apparatus is in position to initiate a new writing operation.

A further object of the invention is to provide operative interconnection between the record material clamping means and the ejecting means therefor.

A further object of the invention is to render the automatic feeding mechanism responsive to certain normal manipulative operations of the writing machine.

A further object is to provide in combination with the automatic material feeding mechanism a differential speed control means by which the speed of operation of the feeding means may be proportioned to the distance through which the material is to be advanced at each operation.

With the above primary and other incidental objects in view, as will more fully appear in the specification, the invention consists of the features of construction, the parts and combinations thereof, and the mode of operation, or their equivalents, as hereinafter described and set forth in the claims.

In the drawings, Fig. 1 discloses a perspective view of the writing machine of the flat bed type. Fig. 2 discloses an attachment for the writing machine removed therefrom. Fig. 3 discloses a side view of the writing machine and Fig. 4 discloses a perspective view of the writing material. Fig. 5 discloses a schematic wiring diagram.

Some flat-bed platen typewriting machines, wherein the typewriter itself travels over the platen, have been equipped with pin wheel feeding devices as disclosed in patent to Sherman et

al, No. 1,500,727, patented July 8, 1924, and patent to Sherman et al, No. 1,529,555 patented March 10, 1925. However, in each of these prior uses a pin wheel feed has been built into the writing machine, which has necessitated the rebuilding of the writing machine, or writing machines have been specially built to accommodate the pin wheel feeding devices. In the instant disclosure the pin wheel feeding device has been 5 mounted upon a frame which is removably mounted upon the typewriting machine and which fits into standard machines that have not been provided with a pin wheel feeding device. In this way the attachment may be adapted to 10 the machine without any alteration of the typewriter.

In addition to being removably mounted, the present device includes a normally inoperative manually controlled motorized driving mechanism 20 for the platen, which includes a switch normally open and arranged in the path of travel of the writing machine, whereby the switch is closed when the writing machine is in a predetermined position, at which time the motorized driving mechanism ejects the used form and presents the succeeding form into writing position in response to manual operations of the operator. This motorized driving mechanism normally rotates throughout a predetermined range during 25 each cycle of operation and includes a differential drive interconnecting the motor to the pin wheel feeding device whereby variations in the differential drive causes the pin wheel feeding device to eject different lengths of forms into writing position during each cycle of operation. A speed control mechanism for the motor permits the different form lengths to be ejected at substantially the same maximum speed, this 30 speed being determined by the quality and quantity of record material used.

Like parts are indicated by similar characters of reference throughout the several views.

Upon the frame 10, having a flat-bed platen 12, is mounted a traveling writing machine 14 that advances over the record material both transversely and longitudinally during the writing operation upon a form overlying the platen. This typewriting machine is generally known to the trade as the Elliott-Fisher typewriter. The writing machine 14 is mounted for transverse movement upon a longitudinally moving carriage 16, provided with toothed wheels 18 that mesh with the racks 20 in the longitudinal rails 22 carried upon the frame 10.

55 A clamp 24, attached to arms 28 pivoted at 30 to the rails 22, engages the advance edge of the record material 32 to hold it in position during the writing operation by the machine 14. A foot treadle 34, connected to a rod 36 having one end pivoted to member 28, releases the clamp 24 whenever it is desirable to eject one form from the writing machine and advance the succeeding form into writing position, or when it is 55 desirable to rearrange or move the form overlying the platen bed.

In the past it has been the common practice for the operator to release the clamp 24 by actuating the treadle 34 with his foot and then pull 70 one form out of writing position and insert another form into writing position. However, this is a slow and tedious operation. In the present modification the written form is automatically ejected and the succeeding form advanced into writing position in response to certain operations

of a form ejecting mechanism which will now be described.

A frame 40 is removably mounted intermediate the rails 22 and carries a pin wheel feed roller 42 driven through a chain of gears 44 from a suitable restricted operation motor 46. The pins 48 are preferably mounted for radial movement in the roller 42, a description of which will not be made at this time for the reason that the movement of the pins with respect to the roller 10 42 may be identical to the disclosure of pin feed device in Sherman's application Serial No. 542-855, filed June 8, 1931. The record material is guided over the pins by a pair of slotted guides 50 resiliently mounted on member 52 suitably 15 attached to the frame 40, so that as the record material is advanced by the feeding pins 48 it is held in engagement therewith by members 50.

The motor is of the restricted operation type like the motor disclosed in the Sherman et al 20 Patent No. 1,741,442 patented December 31, 1929, and will not now be described as the structure is the same.

As the operator actuates the foot treadle 34, the link 56 actuates the bell crank lever 58 connected to another link 60 which is mounted to actuate the plunger 54 of the motor 46. As disclosed in the Sherman et al patent, the plunger 54 closes a pair of contacts 55, shown in Fig. 5, that completes the circuit through the motor. If the circuit is otherwise closed, as will be more fully described later, the motor drives the chain of gears 44, which actuates the feed roller 42 to eject one form length of record material and advances the succeeding form into writing position, at which time the motor stops.

As the clamp 24 is also actuated by the treadle 34, it is desirable to provide another switch in the motor circuit so that the operator may adjust the record material in writing position by 40 actuating the treadle 34 without closing the motor circuit. A push button 64 closes a switch 62, normally held in open position. This switch 62 is mounted upon a bracket 66 carried by the frame 40 and arranged in the path of the carriage 45 16 so that as the typewriter 14 and its carriage 16 is retracted and pushed to the rear, as viewed in Fig. 3, the carriage engages the push button 64 to close the circuit through the motor. When the switch 62 is closed by the carriage 16 engaging 50 the push button 64, the operator may then actuate the treadle 34 to close the switch actuated by the plunger 54 to complete the circuit through the motor.

In order to control the speed of the motor 55 a rheostat 68 is connected in series with one of the leads leading to the motor so as to regulate the speed of the motor.

It is desirable to eject the forms at the maximum rate of speed at which the forms may be 60 fed. Consequently it is imperative to control the speed of the motor so as to decrease the speed when the form lengths are longer and increase the speed for short length forms. That is, the speed must be less where a long form is fed out 65 during one cycle of operation of the motor as compared to the speed when a very short form is fed out during the same operative cycle of the same motor. If a form 13" long were fed out 70 during the same period of time as a 6½" form, the longer form would be fed twice as fast as the shorter. This being the case, if the maximum speed is attained in feeding the 6½" form it is absolutely necessary to decrease the speed of the motor so as to prolong the time for ejecting 75

the longer form in order to keep the speed of the longer form within the range of the maximum practical speed at which the forms may be ejected.

5 The gears 44, disclosed in Fig. 2, may be changed so as to change the gear ratio, thereby changing the effective length of the forms ejected. Holes 90, in the frame 92 supporting the gears 44, may be used for mounting different sized gears so as 10 to secure the proper gear ratio.

10 The frame 40, the pin wheel feed roller 42, the gears 44, the motor 46 and the parts associated therewith are mounted as a unit in standard typewriting machines. The frame 40 is preferably 15 adjustable so that the assembly may be removably mounted in various types and sizes of Elliott-Fisher machines.

15 In the particular modification disclosed, a pack of record material 75, as shown in Fig. 4, has been placed on the stand 70 having one end resting upon a pair of legs 72 and the other end carried by a support 74 mounted upon the writing machine. The pack 75 disclosed in Fig. 4 is provided with continuous length, marginally punched 20 record material 32 having interleaved therebetween continuous length transfer material 76 the holes of which are larger than the holes in the record material, as disclosed in the Sherman Patent No. 1,897,013 patented February 7, 1933. 25 If transfer material that is not of a continuous length is used, the transfer material is preferably placed upon a spool 86 rotatably mounted upon the brackets 82 and 84 carried by the writing machine and extending transversely over 30 the platen. When this type of transfer material is used the feed roller 40 and the pin feed associated therewith eject the record material, forming a loop which is subsequently manually 35 pulled over and under the transversely arranged 40 interleaved sheets of transfer material.

Operation

Whenever it is desirable to eject one form and present the succeeding form into writing position 45 the operator retracts the typewriter 14 upon the carriage 16 until the carriage 16 engages the push button 64 to close the switch 62. Then the operator operates the treadle 34 to release the clamp 24 and actuate the plunger 54 to complete the circuit through the motor 46 which rotates and drives the chain of gears 44 and the pin wheel roll 42 to advance the record material, and 50 trip the motor release, thereby ejecting the used form and presenting a new form into writing position. The operator now releases the treadle 34 which clamps the leading edge of the newly 55 presented form and permits the used form to be torn along the tear line 80. The newly presented form is now in writing position and after it 60 has been written upon the operator again goes through the same cycle of operations to eject one form and present a new form into writing position.

65 Instead of first retracting the typewriter 14, the operator may actuate the treadle 34 to release the clamp 24 and actuate the plunger 54. Then before releasing the treadle, which must remain in the down-position, disclosed in Figs. 1 and 3, 70 until the new form is in position, the operator retracts the typewriter to close the switch 62, thereby closing the circuit through the motor 46. This motor then advances through one cycle of 75 operation to eject the used form, when it comes to a stop. The operator may now release treadle

34 to permit the new form overlying the flat-bed platen to be clamped in position.

From the above description it will be apparent that there is thus provided a device of the character described possessing the particular features 5 of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited 15 to the specific features shown, but that the means and construction herein disclosed comprise the preferred form of several modes of putting the invention into effect, and the invention is therefore claimed in any of its forms or modifications 20 within the legitimate and valid scope of the appended claims.

Having thus described my invention, we claim:

1. The combination with a writing machine of the type wherein a traveling writing mechanism 25 is movable to and fro relative to record material stationarily disposed therebeneath, of strip feeding means for intermittently advancing a strip of record material beneath the writing apparatus to present successive portions thereof in writing position, a one cycle actuating motor therefor, a clamp member for holding the record material in its adjusted position, and multiple control means for the motor including a control 30 means operatively connected with the record material clamp member, and a second control means operated by the movement of the writing mechanism to a predetermined position, the operation of both control means being necessary to the operation of the motor. 40

2. Paper feeding means for a writing machine of the type wherein a traveling writing apparatus is movable to and fro over stationarily disposed record material including a strip feeding device for intermittently advancing record material into writing position, a clamp engaging the material for holding the same in its adjusted position, an actuating motor for the strip feeding means, and means controlling the actuating motor operated by the operation of said record material clamp. 45

3. Paper feeding means for a writing machine of the type wherein a traveling writing apparatus is movable transversely and longitudinally over stationarily disposed record material including a strip feeding device for intermittently advancing record material into writing position, a clamp for holding the material in its adjusted position, an actuating motor for the strip feeding means, and means for controlling the motor operated by the longitudinal movement of the traveling writing apparatus to predetermined position. 55

4. Paper feeding means for a writing machine of the type wherein a traveling writing apparatus is movable to and fro over stationarily disposed record material including a strip feeding device for intermittently advancing record material into writing position, a clamp for holding the material in its adjusted position, an actuating motor for the strip feeding means, and means controlling the motor operated conjointly by the operation of the record material clamp and the traveling writing apparatus. 60

5. In a writing machine wherein a traveling 75

imprinting apparatus is movable to and fro over stationarily disposed record material, record material feeding means for intermittently presenting successive portions of record material in writing position, an actuating motor therefor and a plurality of independently operable motor control devices one of which is manually operated and controlled, the other of which responds to a predetermined position of the imprinting apparatus.

6. In a writing machine wherein a traveling imprinting apparatus is movable to and fro over stationarily disposed record material, record material feeding means for intermittently presenting successive portions of record material in writing position, an electric motor adapted for one cycle operation, an electrical energizing circuit therefor, a plurality of circuit breakers in said circuit, all of which must be closed to energize the motor, and means for successively closing said circuit breakers by the normal operation of the writing machine.

7. In a writing machine wherein a traveling imprinting apparatus is movable to and fro over stationarily disposed record material, record material feeding means for intermittently presenting successive portions of record material in writing position, an adjustable clamp for holding the record material in position, an electric motor adapted for one cycle operation, an electrical energizing circuit therefor, multiple circuit breakers in said circuit, a plurality of which must be closed to energize the motor, means for closing one of said circuit breakers by the adjustment of the imprinting apparatus, and means associated with said clamp for closing another circuit breaker independently of said one circuit breaker.

8. In a writing machine wherein a traveling imprinting apparatus is movable to and fro over stationarily disposed record material, record material feeding means for intermittently presenting successive portions of record material in writing position, an electric motor adapted for one cycle operation, an electrical energizing circuit therefor, a plurality of normally open circuit breakers in said circuit, all of which must be closed to energize the motor, and means under control of the operator for independently closing said circuit breakers, said means including mechanism responding to a predetermined positioning of the imprinting mechanism.

9. In a writing machine wherein a traveling imprinting apparatus is movable to and fro over stationarily disposed record material, record material feeding means for intermittently presenting successive portions of record material in writing position, clamping means engaging the record material for holding the same in adjusted position, an electric motor adapted for one cycle operation, an electrical energizing circuit therefor, multiple circuit breakers in said circuit, a plurality of which must be closed to energize the motor, means for closing one of said circuit breakers by the operation of the record material clamping means, and means for closing another of said circuit breakers independently thereof.

10. The combination with a writing machine having a traveling imprinting mechanism movable transversely and longitudinally over stationarily disposed record material, of record material feeding means for intermittently advancing successive portions of record material into writing position, a one cycle operation motor for ac-

tuating the record material feeding means, and a common control member for the writing machine and said motor, said control member being effective only when the imprinting mechanism is in a predetermined position.

11. The combination with a writing machine wherein a traveling imprinting apparatus is movable transversely and longitudinally over stationarily disposed record material, of record material feeding mechanism for intermittently advancing succeeding form lengths of record material into and out of writing position relative to said imprinting apparatus, an actuating motor therefor, and means for effecting the actuation of the material feeding mechanism by the operation of said motor when the imprinting mechanism is in form length finished position.

12. The combination with a writing machine wherein a traveling imprinting apparatus is movable to and fro over stationarily disposed record material, of record material feeding mechanism for intermittently advancing succeeding portions of record material into and out of writing position relative to said imprinting apparatus, clamping means engaging the record material for holding the same in its adjusted position, an actuating motor for said material feeding mechanism, and means preventing the operation of the material feeding mechanism until the clamping means is disengaged therefrom.

13. The combination with a writing machine wherein a traveling imprinting apparatus is movable transversely and longitudinally over stationarily disposed record material, of record material feeding mechanism for intermittently advancing succeeding form lengths of record material into and out of writing position relative to said imprinting apparatus, an actuating motor therefor, and means preventing the actuation of the material feeding mechanism by said motor until the imprinting mechanism is adjusted to form length finished position for initiating the next writing operation.

14. The combination with a writing machine wherein a traveling imprinting apparatus is movable to and fro over stationarily disposed record material, of record material feeding mechanism for intermittently advancing succeeding portions of record material into and out of writing position relative to said imprinting apparatus, a variable speed actuating motor therefor operable cyclically and means for varying the duration of the cycle so that a speed may be selected compatible with the particular forms used.

15. The combination with a writing machine wherein a traveling imprinting apparatus is movable to and fro over stationarily disposed record material, of record material feeding mechanism for intermittently advancing succeeding portions of record material into and out of writing position relative to said imprinting apparatus, a one cycle operation motor for actuating the material feeding mechanism, and means for regulating the duration of said one cycle of the motor compatible with the length of the material portion to be advanced.

16. A unitary attachment for writing machines wherein an imprinting apparatus travels to and fro over a pair of rails associated with a stationary platen, including a supporting frame removably suspended from the rails, pin type strip feeding mechanism mounted on said removable frame and engageable in marginally punched apertures in continuous strips of record material for advancing such material into writing position.

upon said platen, a motorized driving mechanism for the strip feeding mechanism, and means for intermittently actuating the strip feeding mechanism thereby to eject a portion of record material overlying the platen and advance a succeeding portion thereof into writing position.

17. The combination with a writing machine wherein a traveling imprinting mechanism is movable to and fro, forward and aft, over a stationary platen upon which writing material is received, of intermittently actuated pin type feeding devices progressively engageable in marginally punched holes in a continuous strip of record material, an actuating motor therefor and operative connections from the motor to the pin type feeding devices for actuating the pin type devices to advance the record material through a predetermined range of movement and automatically arrest the movement thereof at the completion of such predetermined range of movement, and means for initiating such operative motion of the pin type feeding devices, only when the imprinting mechanism is in aft position.

18. The combination with a writing apparatus wherein an imprinting mechanism is movable to and fro, forward and aft, over a stationary platen upon which record material is received, of a motorized pin type feeding mechanism for a continuous strip of record material and means for intermittently energizing the pin type feeding mechanism to advance the record material a predetermined distance at each operation and arrest the material at the end of such advance movement, and means for controlling such feeding mechanism by the movement of the imprinting mechanism to aft position.

19. The combination with a writing apparatus wherein an imprinting mechanism is movable to and fro, forward and aft, over a stationary platen upon which record material is received, of a motorized pin type feeding mechanism for a continuous strip of record material and means for intermittently energizing the pin type feeding mechanism to advance the record material a predetermined distance at each operation and arrest the material at the end of such advance movement, operative means common to the writing apparatus and the feeding mechanism for operating one of said mechanisms by the operation of the other, and means responding to a predetermined position of one of said mechanisms for preventing the operation of said other when out of said predetermined position.

20. The combination with a writing apparatus wherein an imprinting mechanism is movable to and fro over a stationary record material receiving platen, of an automatic strip feeding mechanism detachably mounted upon the writing apparatus for intermittently advancing a continuous strip of record material over said stationary platen to present a form length upon the platen, means for initiating the operation of the strip feeding mechanism at the completion of each writing operation upon a form length and means responding to a predetermined position of the imprinting mechanism for preventing said initiating means from operating when the imprinting mechanism is out of said predetermined position.

21. Paper feeding means for an imprinting machine of the type wherein a traveling writing ap-

paratus is reciprocally movable over stationarily disposed record material in a direction normal to the direction of the lines imprinted thereon, including a pin feeding device for intermittently advancing the record material to the imprinting position, said pin feeding device advancing the record material through an arcuate path extending tangentially in the plane of the writing position, an actuating motor therefor and operative connections from the motor to the feeding device for actuating the feeding device to advance the record material through a predetermined range of movement and automatically arrest the movement thereof at the completion of such predetermined movement, and means for initiating such operative motion of the pin feeding device, only when the imprinting mechanism is in a predetermined position.

22. In a writing machine wherein continuous series connected form stationery is intermittently advanced a form length at each operation to present succeeding forms thereof in writing position, releasable detent means for temporarily holding the stationery in its advanced position, a traveling imprinting means operable over the portion of the stationery advanced to writing position, normally inoperative feeding means for intermittently advancing the stationery, and a plurality of control devices conjointly governing the feeding means the operation of each of which is necessary for activating the feeding means, one of said control devices being governed by the travel motion of the imprinting means to a predetermined position and another of the control devices being governed by actuation of said detent means.

23. In a writing machine, a motorized feeding mechanism for intermittently advancing continuous series connected form stationery a predetermined measured distance at each operation to present succeeding portions thereof in writing position imprinting means operatively engageable with the portion thereof advanced into writing position, and duo-control means conjointly governing the operation of the motorized feeding mechanism, dual operation of which is necessary for actuation of the feeding mechanism, said duo-control means being separately operated, by the operation of the imprinting means through a predetermined cycle of operation thereof, and by means controlled by the operator, independently of the operation of the imprinting means respectively.

24. In a writing machine wherein continuous series connected form stationery is intermittently advanced a predetermined distance to present succeeding forms thereof in writing position at each operation, intermittently operated feeding means for advancing the series connected form stationery a predetermined distance at each operation, imprinting means for inscribing the portion of stationery positioned in writing position, and a plurality of independently operable control devices conjointly governing the operation of the feeding means, the operation of each of which is necessary for initiation of the operation of the feeding means, at least one of the control devices being automatically operable by a positioning of the imprinting means and another of the control devices being operable at the will of the operator.

JOHN Q. SHERMAN.

ALBERT W. METZNER.
